DESIGN FOR A BUTTER MEASURING GAUGE

Emma A. Davis, Seattle, Wash.

Application August 8, 1944, Serial No. 114,792

Term of patent 14 years

(Cl. D52—1)

To all whom it may concern:

Be it known that I, Emma A. Davis, a citizen of the United States, residing at Seattle, King county, Washington, have invented a new, original, and ornamental Design for Butter Measuring Gauge, of which the following is a specification, reference being had to the accompanying drawing, forming part thereof, wherein

Fig. 1 is a perspective view of the butter measuring gauge, showing the top side thereof.

Fig. 2 is a perspective view of said gauge showing the under side thereof.

Fig. 3 is an edge view of the gauge.

Fig. 4 is a cross section on the line 4—4 in Fig. 3.

I claim:

The ornamental design for a butter measuring gauge, as shown.

EMMA A. DAVIS.
